COLLAPSIBLE ASH TRAY

Philip K. Madan, Mount Vernon, N. Y.

Application January 20, 1945, Serial No. 573,743

1 Claim. (Cl. 131—240)

1

This invention relates to ash trays. More particularly, the invention deals with devices of this kind which are so constructed as to be packed for shipment in a flat compact package facilitating assemblage of many trays in a small shipping container as well as storage thereof, and which may be readily folded and assembled to form the ash tray. Still more particularly, the invention deals with a tray of the class described which may be composed of inexpensive paper board covered on inner and outer surfaces with a metallic or other facing, rendering the tray substantially fireproof.

The novel features of the invention will be best understood from the following descriptions when taken together with the accompanying drawing in which certain embodiments of the invention are disclosed, and in which the separate parts are designated by suitable reference characters in each of the views; and in which:

Fig. 1 is a perspective view showing the ash tray in assembled position.

Fig. 2 is a perspective view showing the ash tray in collapsed or folded position, also indicating in dot and dash lines the outline of the blank from which the entire device is formed.

Fig. 3 is a section on the line 3—3 of Fig. 2.

Fig. 4 is a section on the line 4—4 of Fig. 1; and

Fig. 5 is a sectional detailed view of the strip of material employed, showing the metallic or other facing sheets thereon.

To illustrate one adaptation of my invention, I have shown in the accompanying drawing a collapsible ash tray formed from cardboard or similar paper board cut to form a blank of the type illustrated in full and dot and dash lines in Fig. 2 of the drawing, this blank comprising an elongated strip divided by score lines into a top wall or section 10, a bottom wall or section 11 joined by a side wall 12. The other side of the top wall 10 includes a foldable side wall portion 13, whereas the free end of the bottom wall includes a securing flap 14 adapted to be secured to the inner surface of the side wall 13, the flap being folded on the line 15, note Fig. 2.

The walls 12 and 13 each have at their ends foldable flaps, the flaps of the wall 12 being designated by the reference character 16 and the flaps of the wall 13 by the reference character 17. The flaps 16 and 17 are adapted to be arranged within end walls 18 and 19 foldable with respect to the top wall 10 on the fold lines 20, the end walls 18 and 19 having foldable flaps 21 and 22 respectively which are adapted to rest upon the inner

2

surface of the bottom wall 11, as clearly seen in Fig. 4 of the drawing.

When assembled, the ash tray forms a box like container of a depth defined by the width of the side and end walls 12, 13, 18 and 19. The top wall 10 has an octagon aperture 23 formed centrally thereof in the manner clearly illustrated in Fig. 1. In forming this aperture, one boundary wall thereof is left with an integral foldable plate portion 24 which is adapted to be folded upon the upper surface of the wall 10 adjacent one corner 25 of the resulting ash tray, and secured to the wall 10 in any desired manner. For example by gluing, stapling or the like. When the tray is assembled all edges of the opening or aperture 23 are arranged inwardly of and in spaced relation to the side and end walls, and the foldable plate portion or member 24 extends over the corner portion of the tray so as to be supported by the top wall and adjacent portions of one of said end walls and one of said side walls.

The plate 24 will form on the resulting ash tray a holder plate, and by attaching the central portion only of this plate to the wall 10, the ends 26 of the plate will be free and have a tendency to curl upwardly to a slight extent to form a holder for retaining a cigar or cigarette against accidental shifting on the tray. It is preferred that the holder 24 be arranged at a corner, such as the corner 25 of the top wall, so that this holder will be contained within the boundaries of the tray when in its collapsed position, as shown in Fig. 2 of the drawing.

From the foregoing, it will be apparent that the complete ash tray is made from a single sheet of material cut and scored to form the resulting tray. In the simpler or more economical form of device, the tray may be composed of a sheet of cardboard or similar paper board faced on both surfaces in any desired manner to render the same substantially flame-proof. One method of procedure would be to simply face the sheet material with metallic facings, such as metal foil.

In Fig. 5 of the drawing is shown a sectional detailed view, slightly in perspective, of a sheet 27 of cardboard or other material having upper and lower facings or facing sheets 28 and 29. These facing sheets are not illustrated in Figs. 1 and 4 in order to simplify the showing. It will be understood, however, that in more practical uses of the invention, facings of flame-proof materials or sheets will be employed, such for example, as metal foil, and when metal foil is used, the foil may be produced in different colors and

may be characterized by embossing to give neat and finished appearances to the resulting tray.

It must be understood, however, that the tray may be composed of any type and kind of material suitable for construction and assemblage in the manner defined, and in some instances, simply characterized cardboard or other paper board may be used, particularly when the ash trays are used for a short period of time and then disposed of.

Basically, an ash tray is designated for the reception of ashes, and not necessarily as a holder for a cigar or cigarette, and from this standpoint, it will be understood that devices of this type and kind having a one use factor can be composed of very inexpensive material, even heavy paper, and used at banquets, dinner parties and the like, and then disposed of in the same manner as a paper napkin or paper dish. Devices of this type and kind will also lend themselves to the application of advertising matter, advertising the restaurant or hotel where the ash trays are used, and may be also characterized by name imprints for home use at bridge parties or other similar occasions.

In some instances, the collapsed containers may be used by merchants for the packaging of merchandise, in which event, the merchant will place the merchandise in the assembled box-like ash tray, thus giving the purchaser a container 30 usable in the home for the intended purpose.

The more elaborate types of trays, namely those having the flame or fireproof characteristics in facings or sheets applied thereto may have a long life use and these trays may be readily 35 cleaned out by simply opening one of the end walls and dumping the ashes from the tray and again closing said end wall.

The upward curling or extension of the ends 26 of the plate 24 can, when desired, be encouraged by the provision of score lines, as indi- 40

cated by dash lines 26' in Figs. 1 and 2 of the drawing.

Having fully described my invention, what I claim as new and desire to secure by Letters Patent is:

A collapsible ash tray comprising foldably related top, bottom, side and end walls, all of said walls being rectangular and having facings of flame resisting material, means including flaps 10 for retaining said walls in assembled relationship, said top wall having a large central octagon opening exposing the interior of the tray, when assembled, for the reception of ashes, all edges of said opening being arranged inwardly of and 15 in spaced relation to said side and end walls, and a member integral with the top wall and foldable directly onto and secured to the top wall to form at one corner portion of the top wall of the tray a cigar and cigarette holder, said member extending over said one corner portion so as to be supported by the top wall and adjacent portions of one of said end walls and one of said side walls.

PHILIP K. MADAN.
